(57) **CLAIM**

The ornamental design for a pill cutting and grinding device as shown and described.

DESCRIPTION

FIG. 1 is a front, top, and right perspective view of a pill cutting and grinding device showing my new design;
FIG. 2 is a rear, bottom, and right perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.
The even spaced broken lines and the blank regions shown in the drawings depict portions of the article that form no part of the claimed design.
